Primary Examiner — George D. Kirschbaum*Assistant Examiner* — Jennifer Watkins(74) *Attorney, Agent, or Firm* — Quickpatents, LLC;
Kevin Prince(57) **CLAIM**

I claim the ornamental design for a facial thermal-pack holder, as shown and described.

DESCRIPTION

FIG. 1 is a perspective view of a facial thermal-pack holder, showing my new design as worn by a person;

FIG. 2 is a right-side elevational view of FIG. 1;

FIG. 3 is a rear perspective view thereof;

FIG. 4 is a front perspective view thereof;

FIG. 5 is a rear elevational view thereof;

FIG. 6 is a front elevational view thereof;

FIG. 7 is a bottom plan view thereof;

FIG. 8 is a top plan view thereof;

FIG. 9 is a right-side elevational view thereof; and,

FIG. 10 is a left-side elevational view thereof.

The broken lines showing a person in FIGS. 1 and 2 depict environmental matter and form no part of the claimed design. The remaining broken lines represent stitching, and are part of the claimed design.
